UNITED STATES PATENT OFFICE.

SILAS W. EMORY, OF VERSAILLES, MISSOURI.

SELF-CLOSING INK-WELL.

No. 891,826.

Specification of Letters Patent.

Patented June 30, 1908.

Application filed August 19, 1907. Serial No. 369,253.

To all whom it may concern:

Be it known that I, SILAS W. EMORY, a citizen of the United States, residing at Versailles, in the county of Morgan and State of Missouri, have invented new and useful Improvements in Self-Closing Ink-Well, of which the following is a specification.

This invention relates to an improved self-closing ink-well, and has for its object to provide a novel construction and arrangement of parts whereby the cover of the well may be swung from over the same and be held for a short length of time in the uncovered position, and then automatically returned to cover the well.

In order that my invention may be clearly understood, I have illustrated the same in the accompanying drawing, in which

Figure 1 is a view in front elevation of my improved device; Fig. 2 is a plan view of the same, and Fig. 3 is a sectional view taken on the line 3—3 of Fig. 2, and viewed in the direction of the arrows.

Referring now to the drawing, 1 indicates the frame of the device, which is preferably rectangular in shape, having at one end an ink-stand 2, and being made hollow as to its remaining portion, thereby providing a top 3 and a bottom 4. The ink-stand 2 is provided with an ink-well 5, the open end of which is at the top of the stand. The upper surface of the stand is flush with the upper surface of the top 3. The ink-stand 2 may be made an integral part of the frame 1, or it may be a separate structure secured therein. The mouth of the well 5 is adapted to be closed by a plate 6, which is secured at one end to the upper end of a post 7 mounted on the outer end of a swinging arm 8. Toward its inner end the arm 8 is pivotally mounted on a rod 9 extending between and secured in the top and bottom of the frame. The top 3 is provided with a recess 10, having a curved side 11, which is adapted to accommodate the swing of the post 7. Mounted on the bottom 4 at a suitable point within the space bounded by the recess 10, and toward the rear side of the ink-stand is a post 12.

The inner end of the plate 6 projects over the recess 10 as shown in Fig. 2, and secured to the inner corner of this plate in any suitable manner and suspended therefrom is a cord 13, having a weight 14 secured on its lower end and held a slight distance above the bottom 4. Mounted on the inner edge

of the plate 6 is a guard 15, the purpose of which is to facilitate throwing plate 6 from over the mouth of the ink-well 5.

In operation the person desiring to dip the pen in the ink of the well 5 simply places the pen-point against the guard 15 and imparts a slight thrust to the same. This will cause the plate 6, post 7 and arm 8 to be thrown inward. The cord 13 depending from the plate 6 will also be thrown inward, and the weight 14, by this movement, and by the action of centrifugal force will be thrown inward and slightly outward. As the point from which the cord 13 is suspended will travel in the arc of the circle in the movement of the plate 6, the result will be to impart a gyratory movement to the weight 14, and the post 12 is so disposed in the path of movement of this weight that at a given point the weight will encircle said post, causing the cord 13 to wind upon the same. By this means the plate 6 will be held at the limit of its inward throw for a short period of time. The cord 14 will next unwrap from the post 12, and as it finally leaves the post, the swing of the weight 14 will cause the post 7 to swing outward and again bring the plate 6 over the mouth of the ink-well 5. A suitable stop 16 may be provided on the bottom 4, or elsewhere, to arrest the swing of the arm 8 when the plate 6 is moved over the mouth of the ink-well 5.

It will be seen that the only action required by the operator in using my improved ink-stand is that of imparting a slight thrust to the guard 15, the remaining movements of the device being automatic.

The drawing illustrates one embodiment of the invention. It will be understood, however, that said invention is not limited to the precise construction or arrangement of parts illustrated.

I claim:

1. A self-closing ink-well having a swinging closure and means operating automatically to maintain the closure temporarily in its displaced position after it has been swung from over the ink-well and automatically to return the closure to a position over the ink-well.
2. In a self-closing ink-well, in combination with a swinging cover, coöperating means for retarding the return of the cover after it has been swung from over the ink-well, and for automatically returning the cover to the position over the ink-well.

3. In a self-closing ink-well, a cover therefore mounted to swing away from and over the mouth of said ink-well, a weighted cord associated with said cover, and a post located in the path of movement of said weighted cord, the combination operating as described.
4. In a self-closing ink-well, in combination with a swinging arm, a cover for said ink-well carried by said arm, and freely movable over the mouth of said ink-well, a weighted cord also carried by said arm, and a post located in the path of movement of said weighted cord, the combination operating as described.
- 15 5. In a self-closing ink-well, in combina-

tion with a swinging arm, a cover for said ink-well carried by said arm and freely movable over the mouth of the ink-well, an upright guard mounted on said cover, a 20 weighted cord also carried by said arm, and a post located in the path of movement of said weighted cord, the combination operating as described.

In testimony whereof I have hereunto set 25 my hand in presence of two subscribing witnesses.

SILAS W. EMORY.
